UNITED STATES PATENT OFFICE.

JOSEPH M. NELSON, OF MINNEAPOLIS, MINNESOTA.

DOOR OPENING AND CLOSING DEVICE.

1,426,901.

Specification of Letters Patent. Patented Aug. 22, 1922.

Application filed December 24, 1921. Serial No. 524,704.

To all whom it may concern:

Be it known that I, JOSEPH M. NELSON, a citizen of the United States, residing at Minneapolis, in the county of Hennepin and State of Minnesota, have invented a new and useful Door Opening and Closing Device, of which the following is a specification.

My invention relates to improvements in door opening and closing devices.

Its object is to provide a simple, durable and inexpensive electrically actuated device of this kind, capable of being easily installed and constructed to avoid injury to the driving mechanism thereof and to the door structure operated thereby.

With the foregoing and other objects in view, which will appear in the following description, the invention resides in the novel combination and arrangement of parts and in the details of construction herein-after described and claimed.

In the drawings, Fig. 1 is a view illustrating, in section, a sliding door structure, and, in plan, the principal parts of an applied door opening and closing device, embodying my invention, said view being taken on the line 1—1 of Fig. 2; Fig. 2 is a vertical sectional view taken on the line 2—2 of Fig. 1; Fig. 3 is a similar view taken on the line 3—3 of Fig. 1; Fig. 4 is a plan view illustrating, in detail, one of the door buffers and associated switch arms, said view being taken on the line 4—4 of Fig. 3; Fig. 5 is a side elevation, in detail, of the driving motor, clutch and a portion of the rod actuated by said motor; Fig. 6 is an end elevation of the same and Figs. 7 and 8 are diagrammatic views illustrating my invention as applied to swinging doors, double and single.

Referring to the drawings in which similar reference letters and numerals have been used to designate similar parts throughout the several views, I have employed the letter A to indicate doors and the letter B to designate the door frames and associated wall structures. In Fig. 1, I have shown a sliding door A, carried by hangers 10 traveling upon a rail 11, on the wall structure B. A threaded actuating rod 12 is secured at one end to a bracket 13 fixed to the door A. A reversible motor C depending from a hanger 14 on the wall structure B (or ceiling, not shown) is equipped with a hollow or tubular driving shaft 15 designed to

freely receive the actuating rod 12. A propelling nut 16 is threaded on said rod 12. Between the nut 16 and one end of the motor shaft 15 is a clutch D for turning said nut with said shaft. This clutch (Fig. 5) includes a driving member 17^a and a driven member 18^a. The clutch driving member 17^a comprises an annular body 19 including a hub 20 secured upon the motor shaft 15. Said body 19 is formed with an annular depression 21 in its outer face and is provided with ears 22 and stops 23. The driven member 18^a of the clutch D includes a circular plate 24 fitted within the annular depression 21 in the body 19. Radial fingers 25, pivoted medially on the ears 22 of the body 19, bear at their inner ends upon the plate 24. The pressure of said fingers 25 against said plate is regulated by means of tension springs 26. These springs encircle threaded stems 27, which abut against the stops 23 on the body 19, said springs being interposed between set nuts 28 on said stems and the outer ends of the fingers 25. A universal joint is supplied between the clutch member 18^a and the nut 16. This joint includes a ring 29 pivoted, through the medium of opposed pins 30, to the nut 16, said ring, in turn, being pivoted, through opposed pins 31, to lugs 32 on the plate 24.

Buffers E and F are arranged at opposite sides of the door A to yieldingly arrest the movements of said door at the extremities of its throws. Each buffer (Fig. 4) includes a bracket 33, which is secured to the wall structure B. Each bracket is formed with a pair of guides 34, a pin 35 being slidably mounted therein. Encircling each pin 35 is a coiled spring 36, the same being interposed between a collar 37 on its respective pin and one of the guides 34. Said springs 36 yieldingly hold the forward ends of the pins 35 in the path of the door A, but yield under increasing tension, when the pins 35 are shifted by pressure of the moving door A. Switches 38^a and 38^b accompany the buffers E and F. Referring to Fig. 4, it will be noted that the arm 38 of each switch is pivoted upon its respective bracket 33, one end thereof having a slidable pivotal connection with the rear end of the adjacent pin 35. In Fig. 1, it will be seen that the free ends of the arms 38 make and break contact with terminals 39. An electrical

circuit including the motor C, also includes the buffer actuated switches and a double switch G, preferably, accessible from an automobile, at a position removed from the door A and protected by a suitably guarded housing (not shown). A lead wire 40, supplies current to either of two branch leads 41 and 42, according to the position of the bar 43 of the switch G. Current from the branch lead 41 reaches the motor C through the switch 38^t and supplementary lead 41^a, while current from the branch lead 42 is conducted to the motor C through the switch 38^e and supplementary lead 42^a. Current from the motor C, supplied thereto through either of the supplementary leads 41^a or 42^a returns to the source of supply through a return wire 44 common to both.

Fig. 1 shows the door A closed. To open said door, the operator, usually by reaching from his automobile, throws the bar 43 of the switch G into position shown in dotted lines, thereby connecting the lead 40 and branch lead 41. Said branch lead 41 being connected with the supplementary lead 41^a, through the switch 38^t, the motor C is turned in a direction causing the nut 29 to pull upon the rod 12 and open the door A. The force of the spring 36 in the buffer E assists in the initial opening movement of the door, thus minimizing resistance against the motor, in starting. Near the end of its opening throw, the door A engages the yielding buffer F, the momentum of said door and motor being thereby gradually diminished. At the end of its throw, the door is brought to rest, due to the interruption of current to the motor C, by the throw of the switch arm 38 of the switch 38^t and the consequent disengagement of said arm from its companion terminal 39. To close the door A, the operator, usually by reaching from his automobile, throws the switch bar 43 into position shown in solid lines, Fig. 1. Current passing to the motor through the branch lead 42, switch 38^e and supplementary lead 42^a, causes said motor to turn in a direction resulting in the closing of the door A, by the thrust of the rod 12. In its initial closing movement, the motor is relieved considerably by the force of the buffer F. The momentum of the door, near the end of its closing throw, is reduced by the buffer E and the motor C is finally stopped by the throw of the switch arm 38 of the switch 38^e. The universal mounting for the nut 29 avoids binding and undue wear, while the clutch D avoids injury to the motor C and other driving parts, in case the door meets with any substantial resistance, while current is supplied to the motor.

One form of motor contemplated, includes a hanger bolt 45, which may turn in its supporting hanger 14 and thus provide a swiveled mounting for the motor. In one of my

alternate forms (Fig. 8), the motor C is swiveled and the rod 12 has a pivotal connection with the door A.

In the alternate form shown in Fig. 7, links 46 join the rod 12 with the doors A. 70

The screw thread connections between the propeller rods and motors, in the various forms illustrated, operate to lock the doors, when the motors are at rest. This feature prevents the swinging of the doors by wind 75 or gravity and also saves the cost of the usually heavy and expensive door locks.

The principal advantages of my improved device reside in the simplicity of structure, ease of application, safety against injury to 80 moving parts and, further, in the door locking feature.

Changes in the specific form of my invention as herein disclosed, may be made within the scope of what is claimed without 85 departing from the spirit of my invention.

Having described my invention, what I claim as new and desire to protect by Letters Patent is:

1. In a device of the class described, the 90 combination with a door, of a threaded actuating rod connected at one end to said door, a motor having a hollow driving shaft freely receiving said actuating rod, and a nut threaded on the rod and rotated by said 95 shaft to shift said rod longitudinally.

2. In a device of the class described, the combination with a door, of a threaded actuating rod connected at one end to said door, a motor having a hollow driving shaft 100 freely receiving said actuating rod, a nut threaded on the rod and a power transmitting clutch joining said shaft with said nut, one member thereof being fixed to the shaft and the other member fixed to the nut. 105

3. In a device of the class described, the combination with a hinged door, of a threaded actuating rod connected at one end with said door, a motor, a swiveled mounting for the motor, said motor having a hollow driving shaft slidably receiving said rod, a nut threaded on the rod, a driven clutch member universally connected with said nut and a driving clutch member fixed to said shaft. 110

4. In a device of the class described, the 115 combination with a door, of a threaded actuating rod connected at one end to said door, a reversible motor having a hollow driving shaft freely receiving said actuating rod, a nut threaded on the rod, a connecting medium, between the motor shaft and nut, holding the latter against endwise movement, and yieldingly imparting to said nut, the rotary movements of said shaft. 120

5. In a device of the class described, the 125 combination with a hinged door, of a threaded actuating rod connected at one end with said door, a reversible motor, a swiveled mounting for the motor, said motor having a hollow driving shaft slidably receiving 130

said rod, a nut threaded on the rod, and a universally compensating connecting medium joining said nut with the motor shaft to turn the nut with said shaft and prevent 5 endwise movement of the former with respect to the latter.

6. In a device of the class described, the combination with a hinged door, of a threaded actuating rod pivotally connected at one 10 end with said door, a reversible motor, a swiveled mounting for the motor, said motor having a hollow driving shaft slidably receiving said rod, a nut threaded on the rod, and connecting means between said nut and 15 motor shaft to turn the nut with said shaft and prevent endwise movement of the former with respect to the latter.

7. In a device of the class described, the combination with a door, of a threaded actuating rod connected at one end thereto, a 20 motor having a hollow driving shaft freely receiving said rod, a nut threaded on the rod, said nut being connected with and driven by the motor shaft, an electrical circuit in which said motor is included, a switch 25 in said circuit to complete and interrupt the same, a second switch in said circuit, and a buffer to yieldingly arrest the movement of the door, said buffer being associated with said second switch and adapted to operate 30 the same.

In testimony whereof, I have signed my name to this specification.

JOSEPH M. NELSON.
